UNITED STATES PATENT OFFICE.

GEORGE J. THEOBALD, OF BOSTON, MASSACHUSETTS.

SADDLETREE.

No. 870,857.

Specification of Letters Patent.

Patented Nov. 12, 1907.

Application filed August 1, 1906. Serial No. 328,663.

To all whom it may concern:

Be it known that I, GEORGE J. THEOBALD, a citizen of the United States, and a resident of Boston, in the county of Suffolk and State of Massachusetts, have 5 invented an Improvement in Saddletrees, of which the following description, in connection with the accompanying drawing, is a specification, like letters on the drawings representing like parts.

This invention relates to harness saddle-trees, and 10 has for its object to provide a novel saddle-tree which is constructed to give a better support to the skirt than saddle-trees as commonly constructed and in which a shorter jockey may be used.

I will first describe one embodiment of my invention 15 and then point out the novel features thereof in the appended claims.

In the drawings, Figure 1 is a rear view of a saddle-tree embodying my invention, one side of said figure showing the saddle-tree in section; Fig. 2 is a top plan 20 view of a portion of one side of the saddle-tree; Fig. 3 is a perspective view; Fig. 4 is a perspective view of the upper portion of the skirt.

The saddle-tree is formed at each side with two side arms 3 and 4 from which project the usual flanges 25 5 and 6. These arms 3 and 4 are connected at the top of the saddle by a bridge-piece 7 over which the back-strap 8 passes as usual. 9 designates the usual turret bridge which also connects the arms 3 and 4.

In my improved saddle-tree the flanges 5 and 6 terminate at the turret bridge 9, and extending from the 30 arms 3 and 4 beyond said bridge are rests 10 which are situated near the lower edge of the arms 3 and 4, as best seen in Fig. 3, the space 11 between the flanges 5 and 6 and the rests 10 being sufficient to receive the skirt 12. 35 The extreme end of the arms 3 and 4 are connected by bridge 13. The skirt 12, which may be of any suitable length, is formed at its upper end as shown in Fig. 4, that is, it is cut away to present the fingers 14.

In applying the skirt to the saddle-tree the two fingers 40 45 are inserted in the openings 11 and extend under the flanges 5 and 6 to which they are secured. The rests 10 furnish a firm support for the skirt which extends clear to the edges thereof, and thus prevents the skirt from breaking down at this point.

20 designates the usual stiffening piece underneath the skirt which is secured to the bridge 13. In most saddle-trees this stiffening piece is about all the support that the skirt has at this point, but by providing the lower ends of the arms 3 and 4 with the rests 10 I have 50 in this improvement provided a solid support for the skirt.

15 designates the usual box through which the back band or strap 8 passes. In most saddle-trees this box is usually situated some distance below the turret-bridge 9, and in order to cover the saddle-tree a comparatively 55 long jockey has to be used. In my present invention I secure the box directly to the rests 10, and said box, therefore, is situated closely adjacent to the turret bridge 9. The distance between the turret bridge 9 and the seat 16 is comparatively small and a short 60 jockey, therefore, is all that is necessary to cover the exposed parts of the saddle-tree.

The skirt is usually made of three or four thicknesses of leather sewed together, and it would be within my invention to use the upper layer of the skirt as the 65 jockey to cover the flanges 5 and 6. Where this construction is employed the lower layers only of the skirt would be to cut out to present the fingers 14, said layers extending beneath the flanges 5 and 6 while the upper layer would extend above said flange and take the 70 place of the usual jockey.

It will be understood, of course, that the layers forming the skirt are sewed together at their edges, as at 18.

My improved saddle-tree is of such a shape that the skirt may be made and the various parts thereof sewed 75 together, and if a jockey is used the edges of the jockey may be sewed to the skirt, as at 19, Fig. 2, and after the parts are thus assembled the skirt and jockey may be slipped onto the frame. This is an advantage over the common construction of saddle-tree in which the parts 80 have to be separately applied thereto.

These saddle-trees are usually cast from some metal, and if a light saddle-tree is desired I may make it of aluminium or some similar material which is light but strong. 85

Having described my invention what I claim as new and desire to secure by Letters Patent is:—

In a saddle-tree, side arms forming a space between them for the back strap, a turret bridge connecting said side arms, flanges extending outwardly and laterally from the upper edges of said side arms, said flanges terminating at the turret bridge, skirt rests 10 extending laterally from the arms beyond the turret bridge, said skirt rests being on a lower plane than the flanges and the space between said rests and the flanges being open, a skirt supported by said skirt rest and having fingers underlying said flanges, and a box through which the back strap passes secured to said skirt rests. 90 95

In testimony whereof, I have signed my name to this specification, in the presence of two subscribing witnesses. 100

GEO. J. THEOBALD.
